UNITED STATES PATENT OFFICE.

GEORGE W. HARRIS, OF ELIZABETH, NEW JERSEY.

IMPROVEMENT IN GAS-RETORTS.

Specification forming part of Letters Patent No. 60,183, dated December 4, 1866.

To all whom it may concern:

Be it known that I, G. W. HARRIS, of Elizabeth, in the county of Union and State of New Jersey, have invented a new and useful Improvement in Gas-Retorts; and I do hereby declare that the following is a full, clear, and exact description thereof, which will enable those skilled in the art to make and use the same, reference being had to the accompanying drawings, forming part of this specification, in which—

Figure 1 represents a transverse vertical section of this invention. Fig. 2 is a horizontal section of my superheater, the line x x , Fig. 1, indicating the plane of section. Fig. 3 is a similar section of my retort, taken in the plane indicated by the line y y , Fig. 1.

Similar letters of reference indicate corresponding parts.

This invention consists in a retort made of clay or other suitable material, and provided with return-passages, either built into it after it is made or formed into its bottom while it is manufactured, in such a manner that steam passed through said passages will be superheated and distributed through the incandescent coal placed in the retort.

It consists, also, in a superheater made of fire-clay or other suitable material, to be used in combination with the retort, in such a manner that the steam is superheated before it enters the retort, and prevented from cooling the same, and, furthermore, the effect of the steam on the incandescent coal in the retort is increased.

A represents a retort, of clay or other suitable material, in the bottom of which are built or formed a series of return-passages, a , through which steam is conducted. While passing through these passages the steam is superheated, and it is distributed throughout the

retort by means of a large number of small holes in the inner end of said return-passages, as shown in Fig. 3.

In order to superheat the steam before it passes into the passages a , a suitable superheater, B, may be built into or introduced in the setting of a bench of retorts. This superheater is made of fire-clay or other suitable material, and it is provided with return-passages b , similar to the passages a in the bottom of the retort. After having passed through the superheater the steam is admitted into the passages a , whence it is distributed through the incandescent coal in the retort. By this arrangement the temperature of the steam is raised to such a degree before it reaches the retort that said retort will not be cooled down, and, furthermore, its final temperature is much higher than it would be without the superheater, and its decomposing effect is increased.

In the manufacture of illuminating-gas, the retort A will be filled with anthracite coal, and by passing superheated steam through the same hydrogen gas will be produced, which is passed through another retort filled with bituminous coal. It is obvious, however, that my superheating attachment may be used with advantage in the ordinary process of manufacturing gas, or in other branches of manufacture.

I claim as new and desire to secure by Letters Patent—

The combination of the fire-clay retort A and superheater B, when arranged as herein specified, to inject the superheated steam at the bottom of the bed of incandescent coal.

GEO. W. HARRIS.
